UNITED STATES PATENT OFFICE.

PATRICK J. LUCEY, OF SOUTH BEND, INDIANA, ASSIGNOR TO LUCEY SLICING MACHINE COMPANY, OF CHICAGO, ILLINOIS, A CORPORATION OF ILLINOIS.

SHARPENING DEVICE FOR SLICING-MACHINE KNIVES.

Application filed July 5, 1922. Serial No. 572,921.

My invention relates to new and useful improvements in sharpening devices for slicing machine knives, and more particularly for rotary circular knives, and has for its 5 main object to provide a sharpening device which will sharpen the knives accurately, and which is inexpensive, simple and durable, and is easy to control.

Another object is to provide such a device 10 in which the points of contact of the sharpener and knife will travel in different directions, in order to effectually sharpen the knife.

Another object is to provide a sharpener 15 with means frictionally engageable with and actuated by the rotary slicing knife for driving the sharpening member.

And another object is to provide such a device in which the sharpener will be driven 20 by the knife, but will move contrary to the knife at its point of contact therewith.

These and other objects and advantages will become apparent from the following description taken in connection with the drawings, in which,

Fig. 1 is a side elevation of my sharpening device mounted on the chain housing of a slicing machine, in engagement with the rotary slicing knife of said machine;

Fig. 2 is an end elevation of the part seen in Fig. 1;

Fig. 3 is a plan view thereof;

Fig. 4 is a vertical sectional view taken on line 4—4 of Fig. 2;

Fig. 5 is a horizontal sectional view taken on line 5—5 of Fig. 4;

Fig. 6 is a side elevation of a modified form of sharpening device;

Fig. 7 is a vertical sectional view thereof, 40 taken on line 7—7 of Fig. 6;

Fig. 8 is a horizontal sectional view on line 8—8 of Fig. 7.

In the form of my invention illustrated in Figs. 1 to 5 of the drawings my sharpening device comprises a supporting base 10, which with the use of suitable slots 11 and fastening members 12 mounts the device adjustably on the chain housing 13 of the slicing machine, adjacent the circular slicing knife 14, which 50 is rotatably mounted on said housing in the usual manner.

The supporting base 10 is provided with a sleeve 15 in which a tubular member 16 is rotatably mounted and is supported for vertical adjustment on a set screw 17 threaded 65 in a nut 18 at the bottom of said sleeve. A handle 19 is threaded or otherwise suitably fastened to the upper end of said tubular member for turning the same in said sleeve.

A shaft 20 is rotatably mounted in an eccentric opening 21 in said tubular member and has a bevel pinion 22 fastened to its upper end, and a wheel 24 is mounted with a set screw 25 for vertical adjustment beneath said pinion, a friction surface 26 of rubber, 60 leather, or the like being provided on said wheel in order to have said wheel effectually driven by the rotating knife 14.

A bracket 27 is eccentrically mounted by means of a collar 28 on the upper end of tubular member 16 and held thereon by a nut 29. The upper end of said bracket is provided with a bushing 30 which supports a rotatable shaft 31 and a pinion 32 fastened on its inner end and in engagement with pinion 22 on shaft 20, a circular sharpener or sharpening member 33 being fastened on the outer end of shaft 31 by means of a pair of washers and a retaining nut 34. A handle 35 is threaded or otherwise suitably fastened to 70 said bracket 27 for moving and holding the sharpener 33 in engagement with the usual bevel edge or annular edge of the knife, with the desired degree of pressure, the sharpening device being so arranged that the sharpener shaft 31 and its supporting bushing 30 are parallel with the plane of the knife 14 while the device is in operation.

In operating this device, the supporting member 11 is adjusted and fastened on the 80 top of the chain box by means of screws 12, and the wheel 24, with its shaft 20 and eccentric tubular member 16, is turned by handle 19 into engagement with the convex side of the slicing knife 14, and is driven by rotation of said knife, the rotation of wheel 24 rotating sharpener 33 by means of pinions 22 and 32 and the connected shafts. In the mean time the sharpener is moved against the edge of the knife by means of handle 35 85 and retained in contact with the edge of said knife with the desired or proper degree of 90 95 100

pressure. To place the device in its inoperative position the handle and connected members 27 to 34 are returned to release position, as shown in dotted lines in Fig. 3.

5 The form of my device illustrated in Figs. 6 to 8 of the drawings comprises the supporting base 40 which is adjustably mounted by means of suitable slots 41 and fastening bolts 42 on top of the chain housing 43 of the usual slicing machine, adjacent the rotary slicing knife 44 of said machine.

10 The supporting base is provided with a sleeve 45 in which an oval stem 46 of a bracket 46' is adjustably mounted by means 15 of a set screw 47. Said bracket is provided with an integral bushing 48 in which the vertical shaft 49 is rotatably mounted, the pinion 50 being fastened to the upper end of said shaft and a collar 51 near the lower 20 end, engaging beneath said bushing. A knuckle 52 is formed at the lower end of said stem and is pivotally connected by means of a knuckle or clevis 53 with the shaft 54 carrying a wheel 55 which is adjustably mounted at the lower end of said shaft and is engageable with the convex side of the slicing knife 44 and driven by the rotation of said knife, said knuckle connection providing a universal joint between 25 said shafts 49 and 54.

30 A bushing 56 is formed at the upper end of an arm 57 extending upward from the end of bracket 46', and a bushing 58 is formed at the upper end of an arm 59 which 35 extends upward from said bracket. A shaft 60 is rotatably mounted in said bushings 56 and 58 and has a pinion 61 fastened to it, which is driven by pinion 50. A sharpening wheel 62 is fastened to the outer end of shaft 40 by means of a pair of washers and a set screw 63 engaging in the end of said shaft.

45 Means is provided for moving the wheel 55 into engagement with the convex side of the slicing knife, said means comprising a lever 65 fulcrumed on a bracket arm 66 extending downward at a slant from the bracket 46'. A collar 67 surrounds shaft 54 and contains a threaded finger 68 which extends loosely through the slot 69 in lever 65 and is retained on said lever by a suitable washer and nut. A stop lug 70 is provided on stem 46 for limiting the release movements of said lever, and a spring 71 is connected with said lever and the bracket 46' for normally retaining said lever against said lug, in release position.

55 In using this form of my invention the device is adjusted in the proper position in contact with the knife, by means of slots 60 41 and bolts 42 on the base 40, and the lever 65 is moved from the position shown in full lines in Fig. 6, to the position shown in dotted lines in said figure, thereby engaging the wheel 55 with the knife, as best shown

in Fig. 7, and rotating shafts 54 and 49, 65 pinions 50 and 61, and sharpener 62. In the mean time the slicing knife 44 is driven by the operation of the machine in the usual manner. The wheel 55 is vertically adjustable on shaft 54, to place it at a 70 greater or smaller radius on the slicing knife and allow for adjusting the speed of the sharpener. Said sharpener may thus be adjusted to be driven at the same peripheral speed as the knife, or at a different speed. 75

It has been found in practice that very desirable results are obtained with either form of my sharpener while traveling at the same linear speed as the slicing knife at the point of contact, these sharpeners being 80 very effective in view of the fact that they rotate in a different direction than does the slicing knife at their point of contact.

85 The sharpener is also arranged to sharpen other articles, such as butcher knives, clevers, etc. For this purpose the wheel 24 of the form of my invention shown in Figs. 1 to 5 is moved into engagement with the slicing knife, as shown in full line positions of said wheel 24 and lever 19 in Fig. 3, 90 while the sharpener with its lever 35 are moved away from the knife, substantially in the dotted line position in said Fig. 3, the article which is to be sharpened being 95 conveniently held against the sharpener and the machine operated in the usual manner. In the form shown in Figs. 6 to 8 the sharpening wheel may be similarly moved away from the knife by loosening bolts 42, while the wheel 45 is retained in contact 100 with the knife.

105 What I claim as new and desire to secure by Letters Patent is:

1. A device for sharpening the bevel edge of a circular rotary knife of a slicing machine, comprising in combination, a rotary knife sharpening member, means driven by the engagement with the side of a knife, operative connections between said knife driven means and said sharpener, and handle means for readily swinging said sharpening member into and out of engagement with said knife. 110

115 2. A device for sharpening the bevel edge of a circular rotary knife of a slicing machine, comprising in combination, a rotary knife sharpening member, means for permanently mounting said member on said machine and for conveniently moving said member toward and from said knife, means driven by engagement with the knife, transmission mechanism between said knife driven means and said sharpening member, and eccentric means for moving said knife driven means into and out of contact with said knife. 120

125 3. A device for sharpening the bevel edge of a convex circular knife of a slicing ma-

chine, comprising in combination, a rotary grinder, a frictional wheel driven by the rotating knife, driving connection for rotating said grinder by said wheel, and means for readily moving said grinder into and out of contact with said knife.

4. A device for sharpening the rotary circular knife of a slicing machine, comprising in combination, a rotary grinder, a frictional wheel driven by the rotary knife, means for rotating said grinder with said wheel, means for moving said grinder into and out of contact with said knife, and a handle with eccentric means for moving said grinder and said wheel together into and out of contact with said knife.

5. A device for sharpening the rotary circular knife of a slicing machine, comprising in combination, a sharpener, means driven by engagement with side of said knife, driving connections between said knife driven means and said sharpener, and means including a screw and a stem supported thereon for adjusting said sharpener radially with respect to the edge of said knife.

6. A device for sharpening the rotary circular knife of a slicing machine, comprising in combination, a sharpener, means driven by engagement with the side of said knife, driving connections between said knife driven means and said sharpener, and means for adjusting said knife driven means radially with respect to said knife to vary the speed ratio between said knife and said sharpener.

7. A device for sharpening the rotary circular knife of a slicing machine, comprising in combination, a knife sharpening member, a bracket for supporting said sharpening member, means engageable with the knife for driving said sharpener, and means for adjusting said knife driven means and said sharpener with respect to each other.

8. A device for sharpening the rotary knife of a slicing machine, comprising in combination, a bracket adjustably mounted on said machine, a shaft rotatably mounted in said bracket, a sharpener fastened on said shaft, a second shaft rotatably and eccentrically mounted in said bracket, gears connecting said shafts, a rotatable member fastened on said second shaft, means for adjusting said shaft and member radially on said knife to vary the speed ratio of said member and knife, and means to move said rotatable member into engagement with said knife to drive said shafts and sharpener.

9. A device for sharpening the rotary knife of a slicing machine, comprising in combination, a supporting base adjustably mounted on said machine, a bracket adjustably mounted on said base, a knife sharpener rotatably mounted on said bracket, a shaft movably mounted on said bracket, a set screw in said bracket to support said shaft,

a member adjustably fastened on said shaft engageable and operable by said knife, and motion transmitting means between said shaft and said sharpener.

10. In a slicing machine having a rotatable circular knife, in combination, a bracket adjustably mounted on said machine, a shaft mounted parallel with the plane of said knife, sharpening means fastened on said shaft, means engaged and driven by said rotatable knife, a handle and eccentric means for readily moving said knife driven means into and out of engagement with the knife, and connecting means for actuating said sharpening means with said knife driven means.

11. In a slicing machine having a convex circular knife, in combination, a shaft, means on said machine for supporting said shaft parallel with the plane of said knife, a rotary sharpener fixed on said shaft, a wheel driven by engagement with the convex side of said knife, mechanism for rotating said shaft by means of said driven wheel, and swingable means for readily moving said sharpener and said wheel together away from said knife.

12. In a slicing machine having a rotatable knife, a supporting base with a sleeve adjustably mounted on said machine, a bracket having a stem with which it is adjustably mounted in said sleeve, a shaft mounted in said bracket, a sharpener mounted on said bracket, driving connections between said shaft and said sharpener, a knife driven wheel, swingably connected with the lower end of said shaft, and means for swinging said driven wheel into engagement with said rotatable knife.

13. In a slicing machine having a rotatable knife, and a chain housing with a rotatable shaft for supporting said knife, a supporting base with a sleeve adjustably mounted on said housing, a bracket having a stem with which it is adjustably mounted in said sleeve, a vertical shaft mounted in said bracket, a swingable shaft having universal joint connected with said vertical shaft, a knife driven wheel adjustably mounted on said swingable shaft, and means for swinging said wheel into action with said knife.

14. A device for sharpening the bevel edge of a circular rotary knife of a slicing machine, comprising in combination, a sharpener, a wheel driven by engagement with the side face of the knife, driving connections between said knife driven wheel and said sharpener, and means including an adjustable member with a shaft carried thereby and means to fasten said wheel on said shaft, for adjusting said wheel radially on said knife to vary the speed of the sharpener with respect to said knife.

15. A sharpening device for a rotary knife of a slicing machine, comprising in combina-

tion, a support mounted on the knife supporting housing of said machine, a sharpening member for said rotary knife, rotatably mounted on said support, a wheel mounted on said support and driven by engagement with said rotary knife transmission mechanism between said sharpening member and

wheel and operating mechanism for retaining said wheel on said knife and said sharpener operative but away from said knife for sharpening articles.

In testimony whereof I have signed my name to this specification.

PATRICK J. LUCEY.
